CONCRETE PILE

Shigeru Watanabe, Tokyo, Japan, assignor to Nippon
Concrete Industries Company, Ltd., Tokyo, Japan

Filed July 9, 1970, Ser. No. 23,887

Term of patent 14 years

Int. Cl. D25—01

U.S. Cl. D13—1

FIG.1 FIG.2 FIG.3

FIG.4 FIG.5 FIG.6

FIG.7 FIG.8 FIG.9

FIG. 1 is a front elevation and a rear elevation of a concrete pile showing my new design;

FIG. 2 is a side elevation as seen from the left of FIG. 1;

FIG. 3 is a side elevation as seen from the right of FIG. 1;

FIG. 4 is a top plan view thereof;

FIG. 5 is a bottom plan view thereof;

FIG. 6 is a cross sectional plan view taken along the line 6—6 of FIG. 1;

FIG. 7 is a cross sectional elevation taken along the line 7—7 of FIG. 4;

FIG. 8 is a cross sectional elevation taken along the line 8—8 of FIG. 4; and

FIG. 9 is a perspective view thereof.

The characteristic features of the instant invention include the novel combination of a column having four perpendicular planar surfaces with semi-cylindrical indentations parallel to each other and running the length

of two opposing planar surfaces, a top planar surface, a cylindrical annulus coextensive and coaxial with the column, a bottom portion defined by three tapered planar surfaces wherein one of the surfaces has an area greater than each of the others.

I claim:

The ornamental design for a concrete pile, as shown and described.
